UNITED STATES PATENT OFFICE.

LOUIS McCUTCCHON, OF HAVANA, CUBA.

DESIGN FOR A TOWEL-HOLDER.

SPECIFICATION forming part of Design No. 33,584, dated November 20, 1900.

Application filed October 26, 1900. Serial No. 34,517. Term of patent 14 years.

To all whom it may concern:

Be it known that I, LOUIS McCUTCCHON, a citizen of the United States, and a resident of Havana, Cuba, have invented and produced a new and original Design for a Towel-Holder, of which the following is a full, clear, and exact description.

Reference is to be had to the accompanying drawing, forming a part of this specification, in which the figure is a perspective view of a towel-holder, showing my design.

The leading feature of the design consists of the configuration of the towel-holder made the subject-matter of the accompanying illustration.

The design in its entirety consists of a pair of closed jaws A A', representing in outline a bottle or a flask appearing divided longitudinally in two parts, an eye B projecting from the mouth of the bottle, the head C of a clamping-screw appearing on one side on one of the jaws, and the opposite faces of the jaws at the lower ends thereof being corrugated or fluted, as indicated in the drawing.

tudinally in two parts, an eye B projecting from the mouth of the bottle, the head C of a clamping-screw appearing on one side on one of the jaws, and the opposite faces of the jaws at the lower ends thereof being corrugated or fluted, as indicated in the drawing.

Having thus fully described my invention, I claim as new and desire to secure by Letters Patent—

The design for the towel-holder, herein shown and described.

In testimony whereof I have signed my name to this specification in the presence of two subscribing witnesses.

LOUIS McCUTCCHON.
